No. 890,512.

PATENTED JUNE 9, 1908.

H. A. HENDERSON.

HINGED LAST.

APPLICATION FILED JULY 23, 1907.

UNITED STATES PATENT OFFICE

HENRY A. HENDERSON, OF LYNN, MASSACHUSETTS.

HINGED LAST.

No. 890,512.

Specification of Letters Patent.

Patented June 9, 1908.

Application filed July 23, 1907. Serial No. 385,157.

To all whom it may concern:

Be it known that I, HENRY A. HENDERSON, of Lynn, in the county of Essex and State of Massachusetts, have invented certain new and useful Improvements in Hinged Lasts, of which the following is a specification.

This invention relates to a transversely divided last comprising a forepart and a heel part, said parts being connected by a hinge in such a manner that the last can be shortened swinging one of the parts out of its operative relation to the other part.

The invention has for its object to provide certain improvements in lasts of this character relating mainly to the hinge which connects the two parts, and the method of securing the hinge to the parts of the last.

The invention consists in the improvements which I will now proceed to describe and claim.

Of the accompanying drawings forming a part of this specification, Figure 1 represents a longitudinal section of a last embodying my invention, the hinge of the last being shown in side elevation. Fig. 2 represents a perspective view of the hinge shown in Fig. 1. Fig. 3 represents a section on the line 3—3 of Fig. 1. Fig. 4 represents a view similar to Fig. 1 showing a somewhat different embodiment of my invention. Fig. 5 represents a view corresponding to Figs. 1 and 4, and showing still another embodiment of the invention. Fig. 6 represents a section on the line 6—6 of Fig. 5.

The same letters of reference indicate the same parts in all the figures.

In the drawings 12 represents the forepart and 13 the heel part of a transversely divided last, the said parts being so constructed and connected that the last may be maintained in the extended operative position shown by full lines in Figs. 1, 4 and 5, but may be shortened by a swinging movement of one of the parts relatively to the other as indicated in Fig. 1, where the heel part is shown by dotted lines as swung out of its operative relation to the forepart thereby in effect shortening the last and permitting a boot or shoe which closely fits the last in its extended position, to be readily removed from the last.

The parts 12 and 13 are provided with reciprocal bearing faces adapted to support the compressive longitudinal strain of the last when the latter is in use in a boot or shoe.

In the embodiments of the invention shown in Figs. 1 and 4, the meeting ends of the parts 12 and 13 are curved to form reciprocal bearing faces, one of which has an outward and the other an inward curvature. In Fig. 1, I show the rear end of the forepart section provided with an outwardly curved bearing face 14, the heel part being provided with an inwardly curved bearing face 15. In the construction shown in Fig. 4, the forepart has an inwardly curved bearing face 14', while the heel part has an outwardly curved bearing face 15'. In each case the curved bearing faces are concentric with the hinge center or joint on which one of the parts of the last is adapted to swing. In the construction shown in Figs. 5 and 6, the fore and heel parts 12 and 13 are provided below the hinge center with flat reciprocal bearing faces 17 18. Above these bearing faces, the ends of the parts 12 and 13 are beveled to form faces 19 and 20 between which is a V-shaped gap or space which permits the swinging movement of one of the parts relatively to the other to shorten the last.

Each of the formations above described is common in lasts of this character. My invention does not reside in the formation of the meeting ends of the parts 12 and 13, but relates particularly to the hinge hereinafter described and to the engagement of the hinge with the fore and heel parts.

In carrying out my invention, I provide a hinge which is composed of two general parts or members articulately bonded, each member including an anchoring plug adapted to enter a hole bored for its reception in the last, the hinge having therefore two anchoring plugs which are substantially parallel with each other when the hinge is in the position it assumes when the last is extended, so that the plugs may be inserted simultaneously in two parallel holes 21 21 bored for their reception in the forepart and heel part. The parts of the hinge are articulately bonded before the application of the hinge to the last, and the provision of the parallel anchoring plugs enables the last to be prepared for the reception of the hinge by the simple operation of boring two parallel holes therein, an operation which is capable of being performed simultaneously by two boring tools. When the hinge has thus been inserted the connection between the parts of the last is completed.

In the construction shown in Figs. 1, 2, 3,

and 4, the hinge comprises two anchoring plugs 22 and 23, the latter having a longitudinal slot in one of its end portions, and a connecting plate 24 which is rigidly affixed to or formed integrally with the plug 22, and has an ear 25 which enters the slot in the plug 23, and is connected with said plug by a pivot pin 26, which constitutes the hinge center. The plate 24 has a shoulder 27 at one side of the ear 25, the said shoulder being arranged to abut against the exterior of the plug 23. The shoulder 27 and the portion of the plug against which it abuts, constitute stop members to limit the movement of the hinge to its extended position. In the construction shown in Figs. 1, 2 and 3, the plug 23 to which the plate 24 is pivoted, is located in the fore part 12, while in the construction shown in Fig. 4, the said plug is located in the heel part 13.

In the embodiment of my invention shown in Figs. 5 and 6, the plugs which are designated by the reference numerals 28 and 29, are connected by plates rigidly attached to the plugs, and connected between the plugs by a pivot pin 30, there being preferably three plates, 31 and 32. The plate 31 is rigidly attached to or formed integrally with the plug 28, and projects between the plates 32, 32, which are rigidly attached to or formed integrally with the plug 29, and are spaced apart to receive the plate 31 between them. The plate 31 is provided with a segmental slot 33, and the plates 32 are provided with a pin 34, which passes through said slot, one end of the slot and the pin 34 constituting stop members which limit the movement of the hinge to the extended position of the last.

The holes 21 which receive the anchoring plugs, are preferably bored from the bottom of the last, and their outer ends are closed by filling pieces after the plugs have been inserted.

It will be seen that in each of the above-described embodiments of my invention, a hinge is provided comprising two parallel plugs adapted to be inserted simultaneously in parallel holes bored for their reception in the last, the hinge having one member which constitutes a rigid stop for the other member and for the corresponding portion of the last when the last is extended, so that the act of applying the hinge to the last to articulate the last with a stop to limit the movement of the parts toward their extended position. In the construction shown in Figs. 1, 2, 3 and 4, the said stop is formed by the plug 23 against which the shoulder 27 on the plate 24 abuts. In the construction shown in Figs. 5 and 6 the stop is the right-hand end of the slot 33, as viewed in Fig. 5, the said end of the slot serving as an abutment

against which the pin 34 abuts. By thus providing a hinge, which also serves as a stop, I obviate the necessity of forming angular shoulders on the meeting faces of the fore-part and heel part, so that said parts may be separated from each other by forming a simple curved or straight cut between the holes bored for the reception of the hinge plugs, and after said holes have been bored.

I claim:

1. A hinge for a transversely divided last comprising two members articulately bonded, each member including an anchoring plug adapted to enter a hole bored for its reception in a last, the said plugs being substantially parallel when the hinge is extended, one member constituting a rigid stop for the other member and for the corresponding portion of the last, when the last is extended.

2. A hinge for a transversely divided last comprising two anchoring plugs adapted to enter parallel holes bored for their reception in a last, and a plate rigidly attached to one plug and pivoted to the other plug, the last-mentioned plug constituting a rigid stop member for the plate and for the corresponding portion of the last when the last is extended.

3. A hinge for a transversely divided last comprising two anchoring plugs, one of which has a slot at one end, and a plate rigidly attached to the other plug, and having an ear pivoted in the said slot and a shoulder which bears on the exterior of the slotted plug when the hinge is extended.

4. A transversely divided last having a hole bored in its forepart and a corresponding hole bored in its heel part, said holes being parallel with each other when the last is extended, and a hinge composed of two members articulately bonded, each member including an anchoring plug inserted in one of said holes, one of said plugs constituting a rigid stop for the other member, and the corresponding part of the last, when the last is extended.

5. A last having a hole bored in its forepart, and a corresponding hole bored in its heel part, said holes being parallel with each other when the last is in its operative form, a transverse cut formed between said holes, and free from angular offsets or shoulders, and a hinge composed of two members articulately bonded, each member including an anchoring plug inserted in one of said holes, said hinge having complementary stops adapted to limit the extension of the hinge and last.

In testimony whereof I have affixed my signature, in presence of two witnesses.

HENRY A. HENDERSON.
